(57) **CLAIM**

I claim the ornamental design for a disposable lighter holder with retracting device, as shown and described.

DESCRIPTION

FIG. 1 is a view of a disposable lighter holder with a retracting device.

FIG. 2 is a side view of the disposable lighter holder with retracting device shown in FIG. 1.

FIG. 3 is a top view of the disposable lighter holder with retracting device shown in FIG. 1; and,

FIG. 4 is a view of the disposable lighter holder with retracting device shown in FIG. 1, with the retracting device shown extended from the lighter holder.
